(57) **CLAIM**

The ornamental design for a motorcycle tire, as shown and described.

DESCRIPTION

FIG. 1 is a front, perspective view of a motorcycle tire of my new design;

FIG. 2 is a front view of my new design, the top, and bottom views being identical thereto;

FIG. 3 is a rear view thereof; and,

FIG. 4 is a right-side view of my new design, the left-side view being a mirror image thereof.

The portion of the tire depicted in broken lines in FIGS. 1 and 4 is not part of the claimed design.

1 Claim, 4 Drawing Sheets

FIG. 1

FIG. 2

FIG. 3
